UNITED STATES PATENT OFFICE.

THOMAS C. LENNOX, OF PITTSFIELD, MASSACHUSETTS, ASSIGNOR TO GENERAL ELECTRIC COMPANY, A CORPORATION OF NEW YORK.

STATIONARY INDUCTION APPARATUS.

Application filed October 26, 1920. Serial No. 419,662.

To all whom it may concern:

Be it known that I, THOMAS C. LENNOX, a subject of the King of Great Britain, residing at Pittsfield, State of Massachusetts, have invented certain new and useful Improvements in Stationary Induction Apparatus, of which the following is a specification.

My invention relates to stationary induction apparatus, such as transformers, some reactors, and the like, which are cooled by the circulation of air over the windings and has for its object an improved arrangement of parts which is readily manufactured and adapted for quickly and efficaciously cooling the windings.

In transformers and the like of the shell type, it has been the practice to dispose the windings in vertical planes, which construction readily lent itself to the circulation of air currents upwardly between the windings. Where, however, in order to get better magnetic balance in the respective parts of the coils, a circular construction is employed, mechanical considerations for securing the parts together not infrequently lead to a core type construction with horizontally disposed disc-coils. The methods heretofore employed in shell type constructions for effecting the circulation of air over the windings are not at all adapted to effecting a circulation of air without pockets over horizontally disposed disc-coil windings. It is with this latter type of winding that my invention is chiefly concerned.

In the practice of my invention, I have provided a novel arrangement of baffles which causes the air or other similar cooling medium to traverse alternate inwardly and outwardly radially disposed paths and thereby cool by convection substantially the whole of the adjacently disposed surfaces of each of the disc-coils comprising a winding of this type.

For a more complete understanding of the nature and objects of my invention, reference should be had to the following detailed description taken in connection with the accompanying drawings in which:

Fig. 1 is a plan view partly in section and Fig. 2 a vertical section of a transformer constructed to embody my invention; while Figs. 3 and 4 show details of certain baffle plates employed in the construction disclosed in Figs. 1 and 2.

Referring now to the drawings, 10 denotes a core of laminated magnetic material, on each leg 11 of which is mounted an interleaved disc-coil winding 12. The coils are themselves held in proper spaced relation by means of insulating collars 13 and radially disposed spacing devices 14 which latter also are made of insulating material. This spaced coil stack is itself insulated from the core by means of insulating cylinder 15.

It will be understood that in transformer construction, to which my invention is particularly applicable, the coils comprising windings 12 are suitably connected and arranged in high and low voltage groups; the collars 13 generally being disposed between such groups.

The core 10 with its windings is surrounded by a casing 20, and placed, when installed, over a pit or air chamber, as indicated at 21 in Fig. 2. This pit 21 is adapted to receive a constant supply of air from a convenient source, such as a fan (not shown), which source communicates with the pit through the passage 22; the pit being adapted to discharge into the casing 20 through one or more openings, such as are shown at 23. The casing 20 has a cover 24 provided with valves 25 adapted to control the passage of air therethrough.

To direct properly the passage of the air through the casing and over the windings, baffling means are employed according to my invention. A top baffle plate 30 (a plan view of which is shown in Fig. 3) has its central portion cut away as at 31 so as to fit down over the top portion of the core 10. The peripheral portion of this baffle has a plurality of deep recesses or openings cut therein, as indicated at 32 but otherwise is shaped to conform with the contour of the casing 20. The projecting portions 33 of the baffle 30 which remain between the recesses, accordingly make a snug fit against the interior sides of the casing 20.

In addition to having the central portion of baffle 30 cut away to fit over the core, it has the end portions of the opening 31 each cut to have a circular contour that will coincide with the end of an insulating cylinder 15 in order to permit the egress of air from between the core and the cylinder.

A similar baffle plate 35 (a plan view of which is shown in Fig. 4) is cut to fit over the bottom portion of the core 10. This baf-

ble is formed to fit against the sides of the casing but is cut away to have recesses of the same dimensions and in the same location as the projecting portions 33 in the baffle 30. Such a recess is indicated at 36 in Fig. 4. The projecting portions 37 of baffle plate 35 thus correspond to the recesses 32 in baffle plate 30.

The baffle plate 35 fits up against the 10 under sides of the coil stacks and has the ends of its central opening cut to correspond with the lower ends of cylinders 15, thereby permitting a current of air freely to enter the space between the core and cylinder 15 from the air pit 21.

When the baffle plates 30 and 35 are in place, it is seen that their openings or recesses are in staggered relation. In order, however, to force the air entering an opening or recess in the lower baffle plate to pass over the coil faces before making egress through an opening or recess in the upper baffle plate, I arrange a number of vertical baffle plates 40, generally radially disposed 20 about the winding stacks to partition off the spaces over the recesses in the lower baffle plate from those under the recesses in the upper plate.

The vertical baffle plates 40 are notched 30 along the inner edges, as shown at 41, so as to fit over the collars 13. This inner edge of each baffle 40 is otherwise straight and preferably fits snugly against the edges of the coils of windings 12 between the spacing 35 devices 14.

From this construction, it is seen that air or other cooling medium from the pit 21 in passing up through the openings in the lower baffle plate, enters a channel with a 40 closed upper end. To find egress the air in such channel is compelled to pass about the edges of the vertical baffles 40 along the side and thence into the adjacent channels which have been partitioned off and provided with closed lower ends but with open 45 upper ends by reason of the staggered relation of the openings employed in the baffle plates 30 and 35. This passage of the air follows generally radial directions inwardly and outwardly over the faces of the coils and about the edges of the baffles 40, which movement has been indicated by the 50 arrows *a* in Fig. 1; the spacing devices 14 serving in this connection as baffles or deflectors to facilitate this radial movement.

It will be observed that the air currents thus moving over the coil faces do not pass in succession over the various coils but pass in parallel streams thereover thus permitting a large volume of air to be quickly and freely circulated through the windings and thereby approaching a substantially maximum cooling effect with a given volume of air. The volume of air passing and hence

the cooling effect may be regulated by means 65 of the valves 25.

Having now described what is at present the best means known to me for carrying out an embodiment of my invention, I would have it understood that such means are 70 merely illustrative and that I do not mean to be limited thereby to the exact details shown nor restricted in the choice of recognized equivalents except as defined in my claims hereunto appended. 75

What I claim as new and desire to secure by Letters Patent of the United States, is:—

1. An electrical apparatus comprising windings enclosed in a casing and arranged in spaced relation along a rectilinear winding axis, and baffling plates extending outwardly from the spaces between said windings and separating the space surrounding said windings into a plurality of channels, said channels being provided alternately with entrance and exit openings for a cooling medium, whereby a cooling medium supplied through said entrance openings is conducted to and from the spaces between said windings and about the inner edges of said 80 baffling plates. 85

2. An electrical apparatus comprising disc-coil windings arranged in spaced relation along a rectilinear winding axis, a surrounding casing, baffle plates disposed within said casing parallel to the planes of said windings and above and below the same, said plates being provided with staggered openings about their peripheries, and radial baffle plates disposed between said first named baffle plates and arranged about said windings in a manner to partition off the spaces below and above said openings whereby a cooling medium entering an opening in one of the first named baffle plates will move in parallel streams about the edge of a radial baffle plate traversing the spaces between said windings to find egress through an opening in another of the first named baffle plates. 100 105 110

3. In transformers and the like, the combination with a core, of horizontally disposed disc-coils arranged in spaced relation on a leg of the same, a casing surrounding the core and coils, horizontal baffle plates fitted over said core above and below said coils and provided with openings about their peripheries arranged in staggered relation, and vertical baffle plates disposed between said horizontal baffle plates in radial arrangement about said coils and placed so as to partition off the spaces respectively below and above the openings in said horizontal baffle plates. 115 120 125

In witness whereof, I have hereunto set my hand this 22nd day of Oct. 1920.

THOMAS C. LENNOX.
